UNITED STATES PATENT OFFICE.

FREDERICK WALDNER, OF ALEXANDRIA, SOUTH DAKOTA.

WRENCH.

1,072,535.

Specification of Letters Patent.

Patented Sept. 9, 1913.

Application filed April 22, 1913. Serial No. 762,811.

To all whom it may concern:

Be it known that I, FREDERICK WALDNER, a citizen of the United States, residing at Alexandria, in the county of Hanson and State of South Dakota, have invented a new and useful Wrench; and I do hereby declare the following to be a full, clear, and exact description of the invention, such as will enable others skilled in the art to which it appertains to make and use the same.

This invention relates to a new and useful wrench.

As one of the objects of the invention, it is the aim to provide two members pivoted together, and provided with angular portions having means including a right and left threaded screw, for coöoperating with the angular portion whereby the jaws of the wrench may be moved relative to one another.

In practical fields, the details of construction of the improved wrench may necessitate alterations, to which the patentee is entitled, provided the alterations fall within the scope of what is claimed.

The invention comprises further features and combinations of parts, as hereinafter set forth, shown in the drawings and claimed.

In the drawings:—Figure 1 is a perspective view of the improved wrench constructed in accordance with the invention. Fig. 2 is a view showing parts in elevation and parts in section.

Referring more particularly to the drawings, 1 and 2 designate two members pivoted together as at 3. Said members are formed with correspondingly shaped angular portions 4 comprising the inclined parts 5 and 6, and 7 and 8. Just beyond the inclined parts 5 and 7, the members 1 and 2 terminate in jaws 9 and 10, the opposing faces of which are recessed at 11, whereby a nut or the like may be easily gripped.

In order to move the jaws 9 and 10 toward and from one another cross heads 12 and 13 are provided, the ends of which are provided with anti-frictional rollers 14, adapted to engage the inner inclined faces of the angular portions 4 of said members, whereby, when the cross heads are moved to separate, the jaws 9 and 10 will be moved apart. To bring the jaws 9 and 10 together U-shaped straps 15 and 16 arch over the inclined parts 5 and 6, 7 and 8, which straps are pivoted upon the pins 17 on which the

rollers 14 are mounted. Springs 18 connecting the said straps at 19 are provided, for holding the straps yieldably in position, thereby allowing the straps to conform readily to the shape of the angular portion 4, as the cross heads are moved toward or from one another, in order to prevent binding, the rollers 14 also constituting means to prevent binding.

A screw device is provided for moving the cross heads apart or toward each other. This screw device comprises a knurled disk 21, from the opposite flat faces of which the pins 22 and 23 extend in opposite directions and axially or in alinement. The said pins are provided with right and left threads, and are threaded through the cross heads, so that upon moving or rotating the disk 21 in either direction the cross heads will be moved toward or from one another. The threads of the pin 23 are somewhat finer and at a different pitch than those of the pin 22, owing to the fact that when the jaws 9 and 10 are separated, the space between the inclined parts 5 and 7 will be greater than the space between the inclined parts 7 and 8. In other words, the cross head 12 should be separated or moved from the cross head 13 faster than the movement of the cross head 13, in order to prevent binding. Only two springs 18 are shown, but it is to be understood that two others are used on the opposite side of the wrench.

The invention having been set forth, what is claimed as new and useful is:—

1. In combination, two members pivoted together and provided with correspondingly shaped angular portions comprising inclined parts, cross heads interposed between and coöperating with said inclined parts, whereby the members may be separated, U-shaped straps arching the inclined parts and pivoted to the cross heads to coöperate with the inclined parts to bring the members together, a screw device comprising a disk member disposed between the cross heads and provided with oppositely extending right and left threaded pins threaded into the cross heads, whereby the cross heads may be moved toward and from one another, said members immediately beyond the angular portions terminating in opposing jaws.

2. In combination, two members pivoted together and provided with correspondingly shaped angular portions comprising inclined parts, cross heads interposed between and

coöperating with said inclined parts, whereby the members may be separated, U-shaped straps arching the inclined parts and pivoted to the cross heads to coöperate with the inclined parts to bring the members together, a screw device comprising a disk member disposed between the cross heads and provided with oppositely extending right and left threaded pins threaded into 10 the cross heads, whereby the cross heads may be moved toward and from one another, said members immediately beyond the angu-

lar portions terminating in opposing jaws, means for yieldably holding the straps in place, and anti-frictional rollers carried by 15 the cross heads to engage the inclined parts.

In testimony whereof I have signed my name to this specification in the presence of two subscribing witnesses.

FREDERICK WALDNER.
